UNITED STATES PATENT OFFICE.

REED ADAMS, OF LAPEER, MICHIGAN.

ATTACHMENT FOR PRINTING-PRESSES.

1,275,824.

Specification of Letters Patent.

Patented Aug. 13, 1918.

Application filed April 7, 1916. Serial No. 89,518.

To all whom it may concern:

Be it known that I, REED ADAMS, a citizen of the United States, residing at Lapeer, county of Lapeer, State of Michigan, have 5 invented a certain new and useful Improvement in Attachments for Printing-Presses, and declare the following to be a full, clear, and exact description of the same, such as will enable others skilled in the art to which 10 it pertains to make and use the same, reference being had to the accompanying drawings, which form a part of this specification.

This invention relates to attachments for printing presses whereby letters can be 15 printed upon a printing press so they have the appearance of a typewritten letter.

The attachments include an automatically-shiftable ribbon which is impressed on the paper to print in the same way that a typewriter prints. This ribbon is carried upon 20 a pair of spools and means is provided for steadyng the spools when the ribbon is being shifted.

A protecting layer of material or frisket 25 sheet is stretched from gripper bar to gripper bar to avoid smudging of the paper by the ribbon. These features will more fully appear in the specification following.

In the drawings,—

30 Figure 1 is a side elevation of a Gordon press, showing my attachments in place.

Fig. 2 is an enlarged detail of the platen and the ribbon and its carriers, the same being an end view.

35 Fig. 3 is a front elevation of the ribbon and its carriers together with the gripper bars and the gripper bar-carrier.

Fig. 4 is a top or plan view of the platen, the ribbon and its carriers.

40 Fig. 5 is a detail showing the pawl and ratchet on the top of one of the spools.

Fig. 6 is a top view partly in section of the same parts.

45 Fig. 7 is a perspective detail of the gripper bars and the frisket sheet showing how the same is fitted on to the gripper bars.

The printing press shown is of the type known as the Gordon press.

50 *a* is the inking plate; *b* the frame into which the type or printing block is locked; *c* the platen; *d* the tympan. The platen and the tympan oscillate back and forth to bring the surface to be printed in contact with the printing block. Inasmuch as this can be accomplished in various ways, it need not be here detailed.

The gripper frame *e* is pivoted at *f* (see Fig. 4) to the platen *c*. The lower end is provided with a follower roll *g* and at each end a pair of uprights *h* having upstanding spindles are riveted or bolted. These spindles rotatably support the long ribbon spools *i* which carry the inking ribbon *j*, which in character is similar to the typewriter ribbon. Each of these spools carries at its top a ratchet wheel having teeth on its side. *k* is a sleeve fixed to the top of the spindle *h*. *l* is a sleeve rotatable about the sleeve *k* but whose rotation is limited at one end by the stop pin *m* and at the opposite end by the spring *n*. *n* *o* *p* is a swinging pawl carrier pivoted at its bifurcated end to the opposite sides of the rotating sleeve *l*. On its end is pivoted the pawl *o*. The full line position of the pawl *o* in Fig. 5 is the operative position. The dotted line position is the inoperative position. Each of the spools is provided with a ratchet and pawl of this character. One pawl must be thrown out when the other is put into engagement with the ratchet teeth. This is indicated in Fig. 3. Each of the pawl carriers is struck by the sides of the platen as indicated in Fig. 4 when the platen swings up to meet the type in the customary way. Hence the 85 pawl carrier on each spool is operated at each time but only one pawl being in engagement with the ratchet teeth, only one spool is operated. Hence the ribbon is made to shift one way by the operation of one 90 pawl and the connected spool. When the ribbon has been nearly wound on this spool, this pawl may be manually disconnected and the other pawl rotated with the ratchet to shift the ribbon in the opposite direction 95 on to the opposite spool.

g, *g* are the customary gripper bars adjustable as to spacing along the slotted bar of the gripper frame *r*. When the form is first locked up a sheet preferably of paper-board 100 is inserted on the tympan and one impression made. This is then taken out and the impressions cut out as shown at *t*, forming the frisket sheet. Rectangular paper bands *u* may be pasted to the back of the frisket 105 sheet at the top and these slipped over the gripper bars as shown in Figs. 7 and 3. The bottom of the frisket sheet is pinched in between the grippers and the gripper carrier. This frisket sheet affords a protection between the ribbon and the main body 110 of the sheet of paper to be printed upon so

that the paper will not be smudged by the ribbon at the places where no type is intended to make impressions upon it.

With the long upstanding spindles it is not possible to make the spools absolutely rigid at the top, and to insure that the spools will be held absolutely rigid while the ribbon is being shifted, I employ a pair of forks *v*, one on each end of the jointed frame *w* which holds the tympan to the platen. When the gripper frame and the platen come together, and before the pawl is engaging the ratchet wheel, these forks straddle the shanks of the screws *x* on the tops of the spindles and thereby securely space the spools and hold them rigid so the ribbon will wind on the spools one convolution in accurate registry with the next below.

What I claim is:

1. The combination of a printing block, a platen, the two being movable relative to each other, a shiftable ribbon between the two and a frisket sheet mounted between the ribbon and the paper to be printed upon to prevent the ribbon smudging the paper at places on the paper where no impression is to be made.

2. The combination of a printing block, a

Copies of this patent may be obtained for five cents each, by addressing the "Commissioner of Patents, Washington, D. C."

platens, the two being movable relative to each other, a shifting inking ribbon, a gripper bar frame provided with a pair of upstanding gripper bars and a frisket sheet adapted to fit over the gripper bars and engage between the ribbon and the paper to be printed upon to prevent the smudging of portions of the paper upon which no impression is to be made.

3. The combination of a printing block, a platen, a pair of upstanding spindles at the ends of the platen and the block, ribbon spools rotatably mounted on the same, a shifting ribbon winding on the spools, and means for engaging the spindles when the ribbon is shifted to hold the spools in rigid position.

4. The combination of a printing block, a platen, the two being movable relative to each other, a pair of upstanding spindles, ribbon spools carried on the same, a shifting ribbon winding on the spools, and forks on the ends of the platen for straddling the spindle tops when the ribbon is being shifted.

In testimony whereof, I sign this specification.

REED ADAMS.
